DESIGN FOR A KEYBOARD FOR CASH REGISTERS

Biagio Beria, Turin, Italy, assignor to Societá
Anonima Officine Di Villar Perosa, Turin, Italy

Application October 7, 1936, Serial No. 65,190
In Italy April 10, 1936

Term of patent 14 years

To all whom it may concern:

Be it known that I, Biagio Beria, a subject of the King of Italy, residing at 154 via Nizza, Turin, in the Kingdom of Italy, have invented a new, original, and ornamental Design for Keyboards for Cash Registers, of which the following is a specification, reference being had to the accompanying drawing, forming part thereof.

The figure is a perspective view of a keyboard for cash registers, showing my new design.

I claim:

The ornamental design for a keyboard for cash registers, as shown.

BIAGIO BERIA.
